UNITED STATES PATENT OFFICE.

FERNAND BOYER, OF PARIS, FRANCE.

PILE-THREAD HOLDER FOR PILE-CARPET MACHINES.

Application filed November 26, 1920. Serial No. 426,434.

To all whom it may concern:

Be it known that I, FERNAND BOYER, manufacturer, a citizen of France, residing at Paris, in the Republic of France, have invented certain new and useful Improvements in Pile-Thread Holders for Pile-Carpet Machines, of which the following is a specification.

The present invention relates to a pile thread holder for pile carpet machines, which grasps the pile thread by means of a gripper while it is being inserted in the carpet and holds it fast, until the formation of the knot has been completed, and at the same time affords such an amount of support to the warp threads, that their divergence during the action of the knotting tools is prevented.

In the drawings I have illustrated a form of apparatus for carrying out my present invention.

Figure 1 is a plan of a pile carpet machine in which my present invention is embodied.

Fig. 2 is a side elevation of the same.

Fig. 3 is a partial cross section taken on line A—A, Fig. 1.

Fig. 4 is also a partial plan showing the parts of the apparatus comprising the present invention, and

Figs. 5 to 14 inclusive are diagrammatic views illustrating the operating parts of the mechanism in different positions in tying a knot in the pile thread and holding the pile thread in position while the knot is being tied therein.

In the apparatus with which the devices comprising my present invention are employed, there are included the same or equivalent form of knotting tools as illustrated in Letters Patent No. 1,180,003 of April 18, 1916 and No. 1,193,229, August 1, 1916. In the use of these devices the warp threads 1 as illustrated in the drawings are stretched in front of the knotting tools

while the pile threads 2 are knotted or tied about the warps so that their free ends form the pile of the carpet. The pile thread 2 is moved by a guide 3 into the path of the grippers 4 and 5 which are closed and hold the thread fast. The guide 3 then moves upwardly so that the carrier pins may move in front of the warps 1 and then the guide 3 moves horizontally and to one side so that the pile thread 2 is caused to lie at an angle to the carrier pin. Behind the warps there

are knotting hooks 7. These move forwardly and backwardly in the guides 8. The guides 8 are also movable horizontally and vertically in all directions irrespective of the positions of the knotting hooks 7. 60 Also in front of the warps 1 there are knotting hooks 9 operating in guides 10. These guides 10 may be swung toward the warps 1 and moved vertically irrespective of the positions assumed by the hooks 9. Also in 65 front of the warps 1 is a movable knife 11. In the operation of these devices after the pile thread has been engaged by the grippers 4 and 5 the guide 3 moves upwardly and sidewise to place the pile thread at an angle 70 across carrier pins 6. The guides 8 then move toward the warps 1 and a pair of hooks for each group of warps pass between the warps so that two warp threads lie between the pair of hooks. These hooks 7 75 then pass over the pile thread 2 and move with the guides 8 downwardly so that the pile thread lies completely in the hooks 7. The guide 3 then moves away and the knife 11 cuts the pile thread projecting from the 80 guide sufficiently far to leave the end of the thread for the next successive operation. When the pile thread has been cut the hooks 7 are withdrawn and carry the ends of the 85 pile thread with them between the warps and the pile threads are then made fast between the hooks 7 and the guides 8. The grippers 4 and 5 and the guide 3 as well as the knife 11 then move away and the guides 8 and the hooks 7 with the pile thread secured therein 90 moved downwardly in order to permit the pile threads to be engaged by the hooks 9. The guide 10 then moves toward the warps and the hooks 9 are moved between the warps to engage the pile threads and to return with the ends of the same in such a manner as to complete the knot in the pile thread, tying the same about the warps. These devices, however, form no part of my 95 present invention.

In Figure 1 the warps are diagrammatically shown, the drawing showing on the left and right hand a number of pile threads 2 with their ends already drawn back over two warp threads 1. 100

According to Figures 2 and 3 the guides 8 for the hook 7 are clamped firmly by means of clamping levers on bars 14, which are held in arms 13 pivotally mounted on both sides of the frame of the machine. 110

Each arm has an eye 15 (see Figure 2) in which a shaft 16 extending right through, rotates. On this shaft are mounted on the left and right double armed levers 17, the lower eyes 18 of which receive a rocking motion from a connecting rod not shown and which act in the opposite direction on the upper eyes 19. In these eyes 19 is mounted a rotating shaft 20 which runs right through 10 and on this shaft are mounted two arms 21 and 22 with bearing eyes 23 and 24 in which the journals 25 of the rotating shaft 26 are carried. On the eyes 24 and 23 are also cast the bar holders 27 and 28 which carry 15 the Z-shaped continuous bar 29 which is rigidly connected to the holders 27 and 28. To one arm 22 is rigidly connected also an arm 30 by means of which the shaft 26 and all the parts carried thereon, including the 20 bar 29 and all the parts on it, can have oscillating movements imparted to them. In the bar 29 are inserted beak-shaped pile thread holders 31 and each two are held fast by means of a screw 32 and a cover 25 plate 33 to the bar 29. Two arms 34 and 35 are mounted on the journal 25 and carry in front the continuous clamping bar 36, which is also connected by connectors 37 to the shaft 26 and can therefore be rocked 30 about the axis of the shaft 26. For this purpose there is rigidly connected to the arm 35 an arm 38 which can be swung by a connecting rod 39 in order to transmit this oscillation to the shaft 26 and to the clamping bar 36 (see Figures 1 and 2). On the clamping bar 36 are mounted clamps 40 which engage in corresponding slots in the pile thread holders 31.

The whole arrangement above described 40 can consequently take part in the general movement of the carrier 13 and at the same time also execute individual movements determined by the connecting rod 39, arm 30 and eye 18. Figure 4 shows the position 45 of the pile thread holders, one such pile thread holder 31 being situated between a pair of hooks 7 and its guides 8.

The action of the apparatus is as follows:—

50 The pile thread 2 is brought in front of the warps 1. The hooks 7 move through the warps and lay themselves across the pile threads in the usual manner. The pulling out and cutting through of the pile thread 55 2 then takes place (see Figure 5). From Figure 5 it can be seen that with the guides 10 the pile thread holder 31 is also brought with the other parts behind the warps 1. The hooks 7 return and take the two ends 60 of the pile thread with them and clamp them fast on the guides 8. During this operation the pile thread holder 31 has been advanced by suitably oscillating the lever 17 (see Figure 2) and by pulling the connecting rod 39 the clamping bar 36 has been

raised. The clamps 40 are protruded from the slots in the pile thread holder 31. This latter moves still further forward by the opposite movement of the connecting rod 39 and the clamping bar 36 is moved downwards, the clamps 40 move into the slots in the pile thread holders 31 and the pile threads 2 are seized and clamped fast (see Figures 7 to 11). The hooks 7 together with the guides 8 move in the direction of the arrow in Figure 13, the hooks 9 pass through the twisted pair of warp threads 1 sideways past the pile thread and seize on their return movement one part of the pile thread 2 (see Figure 8). The hooks 7 next 80 move in the direction of the arrow in Figure 14, the hook 9 advances again and one end of the thread lies under and the other end over the hook 9 (see Figure 9).

After the further advance of the hook 9 85 the second end of the pile thread is also brought into the hook and taken with it on its retirement (see Figures 10 and 11). Both ends of the pile thread 2 are now completely drawn through by the hook 9 and clamped fast at the guides 10 (see Figure 12). At this moment the clamping bar 36 rises by a corresponding pull on the connecting rod 39, the clamp 31/40 is open again and releases the pile thread 2. The 90 pile thread holder as a whole moves back into the starting position again as shown in Figure 5 and until operated again follows the movements of the arms 13. At the same time the hooks 7 as above described move 95 out of the way of the slay 12 the knot is pulled tight and set in place in the usual manner. Figure 13 shows in plan the position of Figure 9. In these figures the 100 main operations of the working of the apparatus are shown and described. By the above described arrangement of a pile thread absolute certainty for the formation of the knot is ensured and consequently also the production of a uniform, fault-free carpet. 110

What I claim is:

1. In a pile carpet machine, the combination with devices for gripping a pile thread and tying a knot therein around warp threads, of auxiliary devices for engaging and maintaining the pile thread in position while the knot is being tied in the said pile thread by the said knot tying devices. 115

2. In a pile carpet machine, the combination with devices for gripping a pile thread and tying a knot therein around warp threads, of auxiliary devices for engaging and maintaining the pile thread and warp threads in position relatively to one another 120 while the knot is being tied in the pile thread by the said knot tying devices. 125

3. In a pile carpet machine in combination with a pile thread feeder, hooks for drawing a pile thread between spaced warp 130

threads, hooks for drawing the ends of the pile thread between predetermined warp threads, and means coacting with the said hooks for gripping the pile thread, of a holder for gripping a pile thread and maintaining the same in position relatively to predetermined warp threads during the knotting operation by the said hooks.

4. In a pile carpet machine in combination with a pile thread feeder, hooks for drawing a pile thread between spaced warp threads, hooks for drawing the ends of the pile thread between predetermined warp threads, and means coacting with the said hooks for gripping the pile thread, of a pile thread holder, a clamp associated with the pile thread holder and adapted to cooperate with the same to grip a pile thread and maintain the same in position relatively to predetermined warp threads during the

knotting operation by the aforesaid hooks, and means for operating the said clamp.

5. In a pile carpet machine in combination with a pile thread feeder, hooks for drawing a pile thread between spaced warp threads, hooks for drawing the ends of the pile thread between predetermined warp threads, and means coacting with the said hooks for gripping the pile thread, of a pile thread holder, a clamping bar, a clamp associated with the pile thread holder, means for operating the said clamp to coact with the said clamping bar to grip a pile thread and maintain the same in position relatively to predetermined warps during the knotting operation by the aforesaid hooks, and means for operating the said pile thread holder.

In testimony whereof I affix my signature.

FERNAND BOYER.
